UNITED STATES PATENT OFFICE.

JAMES H. SMITH, OF BUCKEYESTOWN, MARYLAND.

SHAFT ATTACHMENT.

1,091,024.

Specification of Letters Patent. Patented Mar. 24, 1914.

Application filed January 7, 1914. Serial No. 810,778.

To all whom it may concern:

Be it known that I, JAMES H. SMITH, citizen of the United States, residing at Buckeystown, in the county of Frederick and State of Maryland, have invented certain new and useful Improvements in Shaft Attachments, of which the following is a specification.

The present invention relates to an attachment for the shafts of vehicles, and has for its object to provide a device of this character which embodies novel features of construction for admitting of proper connection being quickly made with the trace and hold back strap without the necessity of wrapping a strap around the shaft in the usual manner.

A further object of the invention is to provide a shaft attachment of this character which is simple and inexpensive in its construction, which is susceptible of expansion and contraction to fit various sizes of shafts, and which is clamped tightly in position upon the shaft so as to reinforce and strengthen rather than weaken the same.

With these and other objects in view, the invention consists in certain novel combinations and arrangements of the parts as will more fully appear as the description proceeds, the novel features thereof being pointed out in the appended claim.

For a full understanding of the invention, reference is to be had to the following description and accompanying drawing in which:—

Figure 1 is a side elevation of a portion of a shaft provided with an attachment constructed in accordance with the invention, strap connections for the hold back strap and trace being shown in position. Fig. 2 is a bottom plan view of the same. Fig. 3 is a longitudinal sectional view through the device, and Fig. 4 is a transverse sectional view through the device.

Corresponding and like parts are referred to in the following description and indicated in all the views of the drawing by the same reference characters.

Specifically describing the present embodiment of the invention, the numeral 1 designates a vehicle shaft which may be of any usual or conventional cross section. An elongated plate 2 is fitted upon one side of the shaft, preferably the top thereof, and extends longitudinally along the same. This plate 2 is transversely curved to con-

form in a very general manner to the curvature of the shaft, the longitudinal edges of the plate having a tapered formation. This plate 2 is preferably formed of spring metal and the thin tapered edges thereof have a sufficient amount of resiliency so that they can be sprung apart or permitted to come together according to the size of the shaft upon which the attachment is to be fitted. Opposite ends of the plate 2 are formed with longitudinally projecting extensions which are returned and coiled to provide eyes 3. These two eyes 3 project outwardly from the shaft and are preferably longitudinally disposed thereon.

A suitable strap connection 4 may be provided for engagement with the hold back strap, the forward end of the strap connection being provided with a snap hook 5 adapted to engage one of the eyes 3. In a similar manner a forwardly extending strap connection 6 is provided which may either terminate in a buckle or like fastening member 7 so as to be attached to the trace, or be directly attached to the hames so as to itself act as a trace. The rear end of the strap connection 6 is provided with a snap hook 8 which detachably engages the forward eye 3. These strap connections can be easily and quickly attached or detached from the eyes 3 as may be desired, and there is no occasion for wrapping a strap around the shaft in the usual manner.

A pair of clamping plates 9 are applied to the shaft on opposite sides of the main plate 2. These plates 9 are elongated and disposed longitudinally upon the shaft and one of the edges of each of the clamping plates overlaps and engages the adjacent side of the plate 2, while the other edge thereof is in direct engagement with the shaft 1. These clamping plates 9 are transversely curved to conform in a very general manner to the shape of the shaft 1 and are also tapered toward the longitudinal edges thereof, as indicated at 9^a. In the construction of these plates 9 spring metal is employed, so that the transversely curved and tapered longitudinal edge portions thereof can spring outwardly to accommodate themselves to various sizes of shafts and at the same time have a very effective clamping action for holding the plate 2 in position.

The tapered edges 9^a of the plate 2, as previously stated, have a yielding action which enables them to be sprung apart and fitted

upon various sizes of shafts. The clamping plates 9 are then placed in position so as to overlap the tapered edges 2^a upon opposite sides of the plate 2. These clamping plates 9 are held in position by means of suitable fastening members such as the bolts 10 which pass transversely through the shaft 1 and corresponding openings in the edges 2^a of the plate 2 and the clamping plates 9. By tightening the bolts 10 the transversely curved clamping plates 9 are sprung into position and caused to fit closely against the shaft and edges of the plate 2. The plate 2 is thus maintained securely in position, and the clamping plates 9 fit tightly against opposite sides of the shaft so as to strengthen and reinforce rather than weaken the same.

In use, it will be obvious that the plate 2 will always be in position upon the vehicle shaft, and that the strap connections 4 and 6 with the respective snap hooks 5 and 8 are connected to the harness and may be almost instantly attached to or detached from the eyes 3 of the device when desired.

Having thus described the invention, what I claim as new and desire to secure by Letters Patent, is:—

In a device of the character described, the combination of a vehicle shaft, an elongated transversely curved plate formed of spring material and adapted to be fitted to the shaft, said plate being provided at opposite ends thereof with outwardly projecting eyes, clamping plates applied to opposite sides of the shaft and overlapping the edges of the first mentioned plate, fastening members for securing the plates in position upon the shaft, and oppositely extending strap connections provided with means for detachably engaging the respective eyes of the first mentioned plate.

In testimony whereof I affix my signature in presence of two witnesses.

JAMES H. SMITH.
